UNITED STATES PATENT OFFICE.

EMMET GAMALIEL SOLOMON, OF OMAHA, NEBRASKA.

YACHT-RACING TOY.

SPECIFICATION forming part of Letters Patent No. 568,808, dated October 6, 1896.

Application filed January 9, 1896. Serial No. 574,856. (No model.)

To all whom it may concern:

Be it known that I, EMMET GAMALIEL SOLOMON, a citizen of the United States, and a resident of Omaha, in the county of Douglas and 5 State of Nebraska, have invented certain new and useful Improvements in Mechanical Yacht-Racing Devices, of which the following is a specification, reference being had to the accompanying drawings, forming a part 10 thereof, in which similar letters of reference indicate corresponding parts.

This invention involves a mechanical device which is intended to represent a yacht-race, and the object thereof is to provide a device of this class which is entirely mechanical and by means of which a comparative representation of a yacht-race may be produced, a further object being to provide a device of this class in which the result of 20 the race between the yachts cannot be foretold, and in which neither of the yachts can be given advantage over the other; and with this and other objects in view the invention consists in the construction, combination, 25 and arrangement of parts hereinafter described and claimed.

The invention is fully disclosed in the following specification, of which the accompanying drawings form a part, in which— 30 Figure 1 is a plan view of my improved yacht-racing device with the upper cover which is applied to a portion thereof removed; Fig. 2, a section on the line 2 2; Fig. 3, a section on the line 3 3; Fig. 4, a section on the 35 line 4 4, and Fig. 5 a sectional detail showing the method of connecting the yachts with the bottom of the device.

In the practice of my invention I provide a bottom board or plate A, which is rectangular in form, and which may be of any desired length and width, and which is provided with vertical side boards a and with vertical end boards a², and the rear portion of which, or that portion in which the operative mechanism is placed, is provided with a cover a³.

The cover a³ is not shown in Fig. 1, it being omitted so as to better show the operative mechanism, which I will now proceed to 50 describe.

The bottom board A is provided adjacent to each side with oblong slots or ways B,

at each side of which are formed flanges b, as shown in Fig. 5, and the yachts employed may be of any desired form and are represented at D, and are provided with keels d, which are free to slide in the ways B, and each yacht may also be provided with a mast d². Mounted at one end of the board is a shaft E, at each end of which is a sprocket-wheel E², each of which is arranged in line with one of the ways B, and mounted on each of said sprocket-wheels is a drive-chain E³, and at the opposite end of the board A is a shaft F, on which are mounted similar 65 sprocket-wheels F², over which said drive-chains E³ are passed. Mounted adjacent to the right-hand side of the board A and near the end in which the shaft F is located is a spring-drum G, the shaft g of which extends 70 through one of the sides of the box or casting, which is composed of the bottom A, the sides a, and the end pieces a², and mounted on the shaft g is a gear-wheel g², which is adapted to operate in connection with a gear-wheel g³, which engages with and operates a gear-wheel g⁴, mounted on the shaft F. Outside of the sprocket-wheels F² on the shaft F are arranged spiral springs F³, one end thereof being adapted to bear upon said 80 sprocket-wheels and the other ends being provided with suitable bearings secured to said shaft, and said springs being adapted to force the sprocket-wheels F² inwardly. These sprocket-wheels F² are free to slide upon the 85 shaft F, on which they are held in place by the springs F³ when the yachts are in motion, there being pins through the main shaft that said sprocket-wheels slip over.

Mounted on the shaft F inside of the 90 sprocket-wheels F² are beveled gear-wheels K, which operate in connection with corresponding beveled gear-wheels k, mounted in line with said shaft outside thereof, and on the shafts of which are mounted drive-wheels 95 k², over which passes a driving-belt k³, which is provided on its outer surface with shoulders or lugs k⁴, which are most clearly shown in Fig. 2, which are adapted to come in contact, when the device is in operation, with the 100 sprocket-wheels F² and to force them outwardly and away from the pin or pins hereinbefore referred to, and thus to allow said wheels to turn faster, thereby running one of

the yachts ahead of the other for the time being. I also provide brakes M, which are semi-circular in form, and the open ends of which are directed outwardly and inclose the shaft 5 F, said brakes being adapted to operate upon the sprocket-wheels F², and said brakes are each provided with inwardly-directed arms m, provided with inwardly-projecting rods m², on which are spiral springs m³, and the inner 10 ends of the rods m² are connected with chains or cords m⁴, which connect with a vertically-movable head or bolt m⁵, Figs. 2 and 3, arranged at right angles to the arms m of the brakes, and said head or bolt m⁵ is provided 15 with a notch in the side thereof, in which operates a horizontal bolt m⁶, which is operated by a spring m⁷, mounted on the rod m⁸, the outer end of which is pivotally connected with two similar levers O and O², which project 20 in opposite directions and which are pivoted at O³ and O⁴, and which are adapted to be operated, respectively, by the yachts D, and when one of the boats reaches the end of the course it strikes against one of the levers, O 25 or O², as the case may be, which operates the spring-operated head or bolt m⁵, by means of which the brakes M are operated, so as to stop both yachts at exactly the same time, and the main shaft and the rubber band k³ 30 will keep on running after the yachts stop.

When it is desired to have a new race, all that is necessary is to pull both yachts back to the starting-point, as there is nothing to prevent it but the brakes M, and they will 35 permit the backward movement of the boats to the starting-point, and when it is desired to start the race all that is necessary is to push down the button P, (shown in Fig. 3,) which operates a bell, (not shown,) and which 40 is connected with the head or bolt m⁵, and which removes the brakes M from contact with the sprocket-wheels F² and at the same time sets the levers O and O², as shown in Fig. 1. When the brakes M are removed 45 from contact with the sprocket-wheels F², the latter slip back on the shaft F, over the pins hereinbefore referred to, and the yachts move as hereinbefore described, and during the time that the yachts are being pulled back 50 to the starting-point the main shaft is running and it runs the rubber band k³ with the rubber shoulders or projections k⁴, formed thereon, so that when the yachts are once started there is no telling where the shoulders or projections k⁴ on the shaft k³ are, and therefore no one can tell which one is 55 going to win the race, as the progress of the yachts will depend entirely upon the operation of these shoulders or projections k⁴ upon the sprocket-wheels F², said sprocket-wheels being turned faster or stopped each time that one of them is struck by one of the shoulders or projections k⁴ on the band k³.

The brake-springs m³ should be stronger 60 than the sprocket-wheel springs F³, and the projections or shoulders k⁴ on the band k³ are of various sizes, thereby giving various moves

to the yachts, or may be arranged in any desired order and any preferred number thereof may be employed, and it is evident that 70 changes in and modifications of the construction herein described may be made without departing from the spirit of my invention or sacrificing its advantages, and I therefore reserve the right to make all such 75 alterations therein and modifications thereof as fairly come within the scope of the invention.

Having fully described my invention, I claim as new and desire to secure by Letters 80 Patent—

1. The herein-described mechanical yacht-racing device, which comprises a bottom board or plate, longitudinal ways in which two yachts are adapted to travel, a shaft 85 mounted transversely at each end of the bottom board or plate, and sprocket-wheels mounted thereon, provided with endless belts which are connected with said yachts, and means for revolving one of said shafts and for 90 moving said yachts, one of said shafts being connected by means of suitable gearing with a spring-drum, and the sprocket-wheels mounted on said shaft being loosely connected therewith, and said shaft being also 95 provided with beveled gear-wheels which operate in connection with corresponding beveled gear-wheels mounted at right angles to said shaft on which are mounted a belt provided with shoulders or projections which are 100 adapted to operate in connection with said sprocket-wheels, substantially as shown and described.

2. The herein-described mechanical yacht-racing device, which comprises a bottom 105 board or plate, longitudinal ways in which two yachts are adapted to travel, a shaft mounted transversely at each end of the bottom board or plate, and sprocket-wheels mounted thereon, provided with endless 110 belts which are connected with said yachts, and means for revolving one of said shafts and for moving said yachts, one of said shafts being connected by means of suitable gearing with a spring-drum, and the sprocket- 115 wheels mounted on said shaft being loosely connected therewith, and said shaft being also provided with beveled gear-wheels which operate in connection with corresponding beveled gear-wheels mounted at right angles 120 to said shaft on which are mounted a belt provided with shoulders or projections which are adapted to operate in connection with said sprocket-wheels, and brakes suitably mounted adjacent to each of said sprocket- 125 wheels, and provided with operating device connected with levers which are adapted to be operated by the yachts, substantially as shown and described.

3. The herein-described mechanical yacht-racing device, which comprises a bottom board or plate, longitudinal ways in which two yachts are adapted to travel, a shaft mounted transversely at each end of the bot-

om board or plate, and sprocket-wheels mounted thereon, provided with endless belts which are connected with said yachts, and means for revolving one of said shafts and for moving said yachts, one of said shafts being connected by means of suitable gearing with a spring-drum, and the sprocket-wheels mounted on said shaft being loosely connected therewith, and said shaft being also provided with beveled gear-wheels which operate in connection with corresponding beveled gear-wheels mounted at right angles to said shaft on which are mounted a belt provided with shoulders or projections which are adapted to operate in connection with said sprocket-wheels, and brakes suitably

mounted adjacent to each of said sprocket-wheels, and provided with operating devices connected with levers which are adapted to be operated by the yachts, and a push-button in operative connection with said brakes, and by means of which the yachts may be put in motion, substantially as shown and described.

In testimony that I claim the foregoing as my invention I have signed my name, in presence of the subscribing witnesses, this 19th day of December, 1895.

EMMET GAMALIEL SOLOMON.
